UNITED STATES PATENT OFFICE.

ARTHUR CLAUSING, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

TRANSMITTER FOR MULTIPLEX ALTERNATING-CURRENT TELEGRAPHY.

Application filed September 9, 1922. Serial No. 587,150.

To all whom it may concern:

Be it known that I, ARTHUR CLAUSING, a citizen of the German Empire, residing at Berlin-Charlottenburg, Germany, have invented certain new and useful Improvements in Transmitters for Multiplex Alternating-Current Telegraphy, of which the following is a specification.

In multiplex telegraphy with alternating-current, the transmitters work generally in such a way that for each frequency a small oscillating thermionic tube is provided which transmits its alternating voltage to the grid of a boosting tube for higher output capacity. The anode circuit of the booster supplies then the pulsating direct current energy in the form of alternating-current energy to the long-distance line to which the boosters of the individual transmitting stations are connected in parallel.

Such an arrangement has the drawback that by the parallel-connection of a plurality of transmitters connected to the line, the energy supplied from one transmitter to the line drops owing to part of said energy being consumed by the other transmitters. The loss of energy is such that with two telegrams about one half, with three one quarter, with four one sixth, and with five one ninth, only of the energy required for each telegram is supplied to the line, as has been proved by theory and experiments.

The present invention has for its object to avoid such useless consumption of energy.

Moreover, another purpose of the present invention is to telegraph at high speed. For this particular purpose it is necessary that the oscillations of the particular frequency are transmitted to the amplifier and to the line immediately at their maximum amplitude at the moment the particular key controlling these currents is closed. It is also necessary for high speed telegraphy that at the moment the key controlling a particular frequency is closed the frequency of that particular oscillator should not vary by the closure of the key, such as for instance through coupling reactances or the like. In other words, each of the thermionic tube oscillators which is used for transmitting should maintain its particular frequency no matter whether the key connecting it to the line is closed or opened.

To obtain these results it is primarily

necessary that no energy, or at least no appreciable energy, is drawn from the thermionic tube oscillator when it is connected to the line. In other words, the several oscillators should not furnish the oscillating energy which is used for the line transmission. This effect may be obtained in well-known manner by using the tube oscillators only as controlling relays, as it were, for a three electrode thermionic amplifier, which as is known, does not require any energy for controlling the grid circuit. In such amplifiers the output current variations are only controlled by the variation of the grid potential.

In order to connect a plurality of thermionic tube oscillators in parallel to a common amplifier, it is also necessary for the successful operation that no feed-back exists between the individual tube oscillators.

According to the present invention this is attained by causing the individual oscillating tubes all to act upon the grid circuit of one single common booster, of which the anode circuit is, as usual, coupled with the long-distance line.

In particular the connection between the oscillators and the common booster or amplifier is made by means of aperiodic circuits, one of such circuits being coupled to the output circuit of each of the oscillators, each aperiodic circuit containing an ohmic resistance which is simultaneously located in the grid circuit of the amplifier.

By keeping the grid circuit of the booster current-less or approximately so, and by properly choosing the anode and grid potentials, almost no energy is consumed at the input side of the booster, because no current flows, but only the potential variations manifest themselves at the grid whereby the sending currents transmitted to the long distance line are controlled.

The accompanying drawing shows a diagram of a transmitting plant according to the present invention.

I, II, III, IV and V designate the individual oscillation or sending tubes. Each oscillation transformer t has a winding t^1 , which is closed over a high-ohmic bifilar resistance W_1 , W_{II} , W_{III} , W_{IV} and W_V and a key T_1 , T_{II} , T_{III} , T_{IV} and T_V , respectively. The high-ohmic resistances are all connected in series, the series being connected at one

side to the grid G of a large boosting tube V and at the other side over a source of grid-bias potential C to the negative side of the cathode F, which is heated by the source A.

5 If, in such an arrangement, no grid current flows in the booster, which can be well attained by an increase of the anode voltage, e. g. by a displacement of the characteristic to the negative region, firstly, the 10 transmitters do not act upon each other and, secondly, a simple addition of the alternating voltages of the individual transmitters takes place. Between grid and cathode of the booster acts the sum of the alternating 15 voltages of the individual transmitters which control the anode current. The anode pulsating current is transmitted over the transformer U to the long-distance line as alternating current.

20 By thus connecting any of the oscillating tubes through their individual key to the booster grid circuit, the oscillating energy of the particular tube is at once supplied at the full amplitude, without variation in frequency, due to reaction. This is rendered 25 possible by the location of the keys T_1-T_V in aperiodic circuits.

Furthermore, since practically no current flows in those aperiodic circuits, substantially no energy is drawn from the individual oscillators I—V when thus connected to 30 the booster grid circuit.

Moreover, it is immaterial for the individual operation of the tube oscillators or transmitters whether one or more of them 35 are at work. If only one transmitter is operating, the remaining transmitters still connected to the grid do not consume or absorb any energy supplied from the first transmitter on account of their connection 40 with the system through aperiodic circuits. One of the advantages of the present system is that the initial cable voltage resulting from one transmitter does not vary by closing the keys of the other transmitters. Besides, the essential advantage is attained 45 that instead of a plurality of boosters, one single large booster only is required.

What I claim, is:—

In a transmitting system for multiplex 50 alternating current telegraphy, in combination a plurality of oscillating current transmitters each comprising a thermionic tube and its associated circuits, an aperiodic circuit for each transmitter, suitably coupled 55 to its circuits, and containing an ohmic resistance and an operating key, and one common thermionic tube amplifier for all of said transmitters having a grid circuit in which the resistances of all of said aperiodic 60 circuits are arranged in series.

In testimony whereof I affix my signature.

ARTHUR CLAUSING.
